UNITED STATES PATENT OFFICE.

JOHN H. HAWLEY, OF NEW YORK, N. Y.

DESIGN FOR A BUTTON.

45,993.

Specification for Design.

Patented June 23, 1914.

Application filed March 31, 1914. Serial No. 828,635. Term of patent 3½ years.

To all whom it may concern:

Be it known that I, JOHN H. HAWLEY, a citizen of the United States, and a resident of the borough of Manhattan, city and State of New York, have invented a new, original, and ornamental Design for Buttons, of which the following is a specification.

My design is represented in the accompanying drawing in which:

Figure 1 is a plan view. Fig. 2 is a side view. Fig. 3 is a side view at 90 degrees from the position shown in Fig. 2. Fig. 4 is a section on line 4—4 of Fig. 3, of a button illustrating my new design.

The design consists of the ornamental shape shown.

I decorate the surfaces of the button to

have a mottled appearance, consisting of a multitude of relatively light and relatively dark minute dots. The dots are of varying areas and shapes and blend with those adjacent thereto.

I claim:

The ornamental design for a button as shown and described or any colorable imitation thereof.

In testimony that I claim the foregoing as my own, I have hereto affixed my signature in the presence of two witnesses.

JOHN H. HAWLEY.

Witnesses:

JOHN J. RANAGAN,
AGNES C. O'CONNELL.
